SHEET METAL DOOR CONSTRUCTION

Warren J. Williams, Richmond Hill, N. Y., and
Carl A. Anderson, Cranford, N. J.

Application November 30, 1951, Serial No. 259,062

1 Claim. (Cl. 189—46)

1

This invention relates to improvements in a sheet metal door construction and has particular reference to doors which are constructed by forming, of pressed sheet metal, a pair of practically similar units which are interlocked to form a door.

The object of this invention is the provision therein of a door constructed of a pair of basic elements which are interlocked and a minimum number of minor parts which are secured to the basic elements with a few spot or tack welds to fix all parts permanently together.

The invention consists of forming a pair of almost similar flanged panel members having guide and interlocking units formed upon the flanges of the panel members.

The best embodiment of the invention has been chosen for illustrative purposes, but this embodiment should be viewed as being illustrative only and not as limiting because obviously the invention is capable of other embodiments having revised details of construction so long as they fall within the ambit of the appended claims.

The invention itself, however, both as to its organization and its method of operation, will best be understood from the following description of a specific embodiment when read in connection with the accompanying drawing, in which:

Fig. 1 is an elevational view of a door constructed of members and assembled as outlined in this description of the invention.

Fig. 2 is a diagrammatic plan view taken along line 2—2 of Fig. 1, and outlines a door set between door jambs.

Fig. 3 is a perspective view of a fragment of a door in which a sectional portion is taken along line 3—3 of Fig. 5.

Fig. 4 is an enlarged sectional plan view of a door, with central portion of same broken away and is also taken along line 2—2 of Fig. 1.

Fig. 5 is an enlarged sectional, elevational view taken along line 5—5 of Figs. 1 and 4.

Fig. 6 is an enlarged fragmentary detail showing the end portion of a pair of opposing panel units about to be assembled.

Fig. 7 is a section along the broken line 7—7 of Fig. 6.

Fig. 8 is a view similar to Fig. 6 but shows the panel units assembled and interlocked.

Fig. 9 is a sectional view taken along line 9—9 of Fig. 8.

Fig. 10 is an inside plan view of a single panel unit.

Fig. 11 is an elevational view, somewhat simi-

2

lar to Fig. 6, but showing the outer surface of flanges formed along one edge of the panel units.

Fig. 12 is a cross section taken along the line 12—12 of Fig. 11.

Fig. 13 is a view similar to Fig. 11, but shows the flanges brought together and interlocked, and

Fig. 14 is an enlarged isometric perspective of one end of the panel units and shows parts broken away.

Referring in detail to the parts, in which similar letters represent similar parts throughout, 11 designates generally a door constructed of parts formed and assembled as outlined in this description and illustrated in the drawings and forming the essential features of this invention.

A pair of panels 12 and 13 (see Fig. 3) have flange formations 14 and 15 along the opposite longitudinal edges of the panel 12. The opposite edges of the panel 13 have flanges 16 and 17. When the two panels 12 and 13 are brought together the edges of the flanges 14 and 15 abut the edges of the flanges 16 and 17 along the lines 18 and 19 respectively. In order to hold the opposing flanges of the panel units together and lock them in place, there are provided elongated rectangular guide members 20 (see Figs. 3, 6 to 10 inclusive and 14), which are spaced upon and extend upwardly from the flange 16 of the panel 13. The said rectangular guide members 20 are integrally formed upon the flange 16 and are offset therefrom to form ledges 21 along their lower edges. Upon the opposing flange 14 there are integrally formed thereon spaced guide members 22 which are adapted to pass through the spaces between the guide members 20 and are integrally formed upon the flange 14 with offset ledges 23 formed along their upper edges. The guide members 22 are notched at one end, as at 24, to form fingers or hooking prongs 25, which prongs are adapted to engage under the ledges 21 upon the guide members 20. Fig. 6 shows the two panels 12 and 13 pulled apart with the guide members 22 in line with the spaces between the guide 20, just before assembly. The arrows X show the direction of movement when the two parts are brought together. Fig. 8 shows the two panels 12 and 13 assembled and the panel 12 carrying the guides 22 moved forward to slide

50 the hooking prongs 25 under the ledges 21 and thereby lock the two panel plates 12 and 13 together along one edge; namely along the flanges 14 and 16.

Similar guide formations, differing slightly as 55 will be explained, are formed upon the flanges 15

and 17. Upon the said flanges 15 and 17 (Figs. 11, 13 and 14) offset rectangular guide members 20' are integrally formed and guide members 22' with hooking prongs 25' are integrally formed upon the flange 17 and offset therefrom. Figs. 3, 8 and 13 show the two panel members 12 and 13 as they appear when assembled and interlocked.

In Figs. 3 and 4 there is shown L-shaped reinforcing ribs 26 having one end 27 spot welded to the panel 12 and their inwardly extending face ends having a T-shaped formation 28. Similar L- and T-shaped reinforcing ribs 29 are spot welded to the panel 13 and extend inwardly therefrom. The reinforcing ribs 26 and 29 are interspersed as best shown in the diagram of Fig. 2. A 15 door assembled as described has open top and bottom ends. To close these ends there is provided channel members 30 and 31 which are inserted at top and bottom (Fig. 5) respectively and are spot welded thereto. Over the channels 30 and 31 20 there are inserted finishing plates 32 and 33 respectively which are tack welded.

Depressed portions 34 are formed to provide recesses to receive hinges and a pocket 35 may be formed upon the opposite edge to receive a locking 25 and latching member.

I claim:

A sheet metal door comprising two opposed flat walls, interlocking continuous flanges at right angles to the vertical sides of said flat walls, said 30 flanges extending half the thickness of said door and adapted to abut each other, guide members offset the thickness of the sheet metal and extending from the edge of said flanges of said flat

walls each of the guide members on said flanges of one flat wall having fingers for interlocking in parallel relationship with said guide members of the other of said flanges on the opposed flat wall, said guide members arranged alternately along said flanges, top and bottom channel members between said flat walls for reinforcing said door, T-shaped vertical reinforcing members, said reinforcing members having flanges for attaching said reinforcing members to the inner faces of said flat walls, said reinforcing members alternately attached to the inner faces of said opposed flat walls, the T-shaped end of each of said reinforcing members extending less than the thickness of said door.

WARREN J. WILLIAMS.
CARL A. ANDERSON.
